[57] CLAIM

The ornamental design for the locking bracket for holding tie rod ends employed with concrete formwork, as shown and described.

DESCRIPTION

FIG. 1 is a top, front, and left side perspective view of a locking bracket for holding tie rod ends employed with concrete formwork showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and

FIG. 8 is a top, rear, and right side perspective view thereof.
